UNITED STATES PATENT OFFICE.

JOHN A. LARSEN, OF ST. OLAF, IOWA.

BAG HOLDER.

Application filed March 25, 1926. Serial No. 97,346.

The invention relates to improvements in devices for suspending bags and holding them open, while they are being filled, for instance with grain, and the object of the 5 invention is to provide a new and improved device of this character which, while being exceptionally simple and inexpensive, will be highly efficient and desirable.

With the foregoing in view, the invention 10 resides in the novel subject matter hereinafter described and claimed, a description being supplemented by the accompanying drawing.

Figure 1 is a front elevation.
15 Figure 2 is an edge view.

Figures 3 and 4 are respectively vertical and horizontal sections as indicated by lines 3-3 and 4-4 of Figure 1.

Figure 5 is a view similar to Figure 4 but 20 illustrating a different position of the swingable bag-holding bracket.

In the drawing above briefly described, the numeral 6 designates a vertically disposed sheet metal plate preferably tapered 25 somewhat at its upper portion, the side edges of this plate being rearwardly bent to provide reenforcing flanges 7 which also have an additional function to be hereinafter set forth. The lower edge of the plate 6 is bent 30 rearwardly to provide an additional reenforcing flange 8 which, like the flanges 7, also possesses another function which will be explained later. If desired, the upper end of the plate 6 may be bent to provide 35 a reenforcing flange 9. In the preferred form of construction, this upper end of the plate is formed with an opening 10 to receive a hook, nail or the like 11 driven into a wall 12, so as to support the plate in a vertical position and permit swinging of said 40 plate toward and from the wall.

The lower end of one of the flanges 7 constitutes carrying means for a stationary bag engaging hook 13; the other of these 45 flanges constitutes carrying means for a swingable bracket 14 having a hook 15 to engage a bag, and the flange 8 serves to carry two additional stationary hooks 16. All of the hooks cooperate in holding a bag in 50 open position while it is being filled, a portion of the bag then extending behind the lower end of the plate 6, as will be clear from the dotted line 17 in a number of the figures, indicating the bag.

55 The hook 13 is preferably of L-shape, with its vertical portion 18 secured to the ad-

jacent flange 7, by rivets 19 or other desired means, the horizontal part of said hook being extended forwardly from the plate 6. The two hooks 16 are preferably formed from single pieces of sheet metal whose body portions are horizontally positioned and secured to the flange 8, rivet 20 being preferably used. The rear ends of these metal pieces are tapered and upwardly bent to provide the bag 60 engaging portions of the hooks, and these upwardly bent ends will rest against the wall 12 when the device is suspended in operative position.

For the swingable bracket 14, a rather 65 unique construction has been provided. This bracket, in the present form of the invention, is shaped from a single length of metal rod. One end portion 21 of this rod constitutes a straight vertical shaft which 70 is rotatable in a pair of bearing eyes 22 secured to the adjacent flange 7. At the lower end of shaft 21, the rod projects horizontally forming an arm 23 which carries the hook 15 at its front end. At the free end 75 of the arm 23, the rod is doubled back upon said arm as indicated at 24, and this portion 24, together with the free end portion of the arm 23 are preferably hammered and welded together, and bent upwardly to form the hook 15. At the inner end of the portion 24, the rod extends upwardly and inclines toward the upper end of the shaft 21 to provide an inclined brace 80 25, the upper end of this brace being bent 90 to provide an eye 26 which surrounds the upper portion of the shaft 1 and rests upon the uppermost of the bearing-eyes 22, so as to support the bracket 14 against descent.

By constructing the bracket 14 in the novel 95 manner shown and described, it may be easily constructed, yet regardless of its simplicity, will be rigid and will well perform the functions for which it is designed. A coiled torsion spring 27 surrounds the shaft 100 21 of this bracket, between the bearing eyes 22, one end 28 of said spring being engaged with a suitable part of said bracket, such as the brace 25, while the other end 29 of said spring may well engage the front side of 105 the plate 6. Thus, the spring acts to normally swing the bracket 14 away from the stationary hook 13, so that when said bracket is swung inwardly upon application of the bag to the device, the outward force of the 110 spring upon the bracket, will hold the mouth of the bag open and will retain it in a taut

position, so that it may be easily filled. To limit the outward swing of bracket 14, when no bag is being held by the device, a stop pin 30 is preferably secured in an opening in the upper end of the shaft 21, said pin being adapted to strike the adjacent flange 11, as shown in Figure 5.

In using the device, it is suspended upon a nail or the like so that it is disposed at the side of a wall, and its lower end may be swung outwardly to first engage the bag 17 with the stationary hooks 16. Then, this bag is passed into engagement with the hook 13 and while the bracket 14 is swung inwardly, the bag is pulled upwardly at the outer side of said bracket, so that upon release of the latter, hook 15 will engage said bag as shown in Figure 4. Thus, the bag is supported with its mouth held wide open and any grain or the like with which the bag is to be filled, is guided into the same to quite an extent by the plate 6.

Particular attention is directed to the combined functions of the flanges 7 and 8, the former serving not only as reenforcing means for the plate 6 but acting also as carriers for the stationary hook 13 and the bracket 14, while in addition to transversely reenforcing the plate, the flange 8 serves as carrying means for the additional stationary hooks 16. Special attention is also invited to the simple yet efficient and desirable construction of the bracket 14.

As excellent results are obtainable from the details disclosed and such details have proven most desirable in actual practice, they are preferably followed. However, within the scope of the invention as claimed, slight variations may be made.

40 I claim:

1. A bag holder comprising a vertical plate, reenforcing flanges bent rearwardly from the vertical edges of said plate, an additional reenforcing flange bent rearwardly from the lower edge of said plate, a stationary hook secured to the lower end of one of said vertical flanges and projecting forwardly from the plate, a swingable bracket pivotally mounted on the lower por-

tion of the other of said vertical flanges and 50 having a hook for movement toward and from the first named hook, an additional stationary hook secured to and projecting rearwardly from the horizontal reenforcing flange at the lower end of the plate; together 55 with means for holding said bracket in operative position when moved to the required extent away from the first named hook.

2. In a bag holder, a support having bearing means, a bracket supported by said bearing means, said bracket being formed from a single metal rod having a vertical shaft portion received in said bearing means, the rod being bent to provide a horizontal arm at the lower end of said bearing means and being bent inwardly upon the free end portion of said arm, this inwardly bent portion and said free end portion of the arm being jointly bent upwardly to provide a bag engaging hook, the rod being inclined toward the upper end of the aforesaid shaft portion from the inner end of said inwardly bent portion to provide a brace, the upper end of this brace being bent to form an eye which surrounds the upper end of the aforesaid shaft portion and rests upon said bearing means; and spring means surrounding said shaft portion of the bracket, said spring means acting against said bracket to laterally swing the same and reacting against 70 said support.

3. In a bag holder, a swingable bracket bent from a single metal rod, one end portion of said rod being straight and forming a vertical shaft, the rod being horizontally 85 bent at the lower end of said shaft to form an arm and being bent inwardly at the free end of said arm, this inwardly bent portion and the free end of said arm being jointly bent upwardly to provide a hook, the 90 rod being inclined toward the upper end of the aforesaid shaft from the inner extremity of said inwardly bent portion to provide a brace, the upper end of said brace being bent around the upper end of said shaft.

In testimony whereof I have hereunto affixed my signature.

JOHN A. LARSEN.
